UNITED STATES PATENT OFFICE.

JOHN DANNER, OF CANTON, OHIO.

REVOLVING BOOK CASE AND STAND.

SPECIFICATION forming part of Letters Patent No. 293,151, dated February 5, 1884.

Application filed August 2, 1883. (No model.)

To all whom it may concern:

Be it known that I, JOHN DANNER, a citizen of the United States, residing at Canton, in the county of Stark and State of Ohio, have invented certain new and useful Improvements 5 in Revolving Book Cases and Stands, of which the following is a specification, reference being had therein to the accompanying drawings, in which—

10 Figure 1 is a perspective view of the book-case. Fig. 2 is a vertical section thereof; and Fig. 3 is a detached view, in perspective, of one of the shelf-supports.

15 My invention relates to revolving stands for the support and exhibition of books and other articles; and the objects of my improvements are to provide an inexpensive revolving stand of strong construction and fine appearance, capable of being packed and shipped 20 in the knockdown form, in a box of comparatively small size, and of being put up again in a few minutes without the help of any tool. I attain these objects by the construction illustrated in the accompanying drawings, in 25 which similar letters of reference refer to similar parts throughout the several views.

In the drawings, A represents a cylindrical metal shaft, having its screw-threaded lower end inserted into a metal support, A', formed 30 with arms that are secured to the bottom frame, A², and the latter is provided with casters upon which the device can be rolled on the floor.

Upon the shaft A is mounted a frame, preferably made of lumber. This frame is composed of two vertical pieces, B, united at the top by a transverse piece, B', and at the bottom by a transverse piece, B², through which the lower end of the shaft passes.

40 To the under side of the transverse piece B' is attached a pendent conical journal, b', that rests into an oil-receiving conical cavity or bearing formed into the upper end of the shaft.

45 To the top edge of the transverse piece B' is secured an ornamental railing, B³, if desired, to improve the appearance of that portion of the stand.

To support the shelves C and the dividing 50 boards D, there is secured to the outer edge of the vertical pieces B of the frame a series of ornamental open-work castings, E, by

means of screws b, passing through (preferably) two openings or slots, e, made vertically one above the other in the central portion of 55 the said castings. The lower portion of the slots e is made wider than the upper portion, to admit the head of the screws b, inserted in advance at regular distances apart into the sides of the frame, the narrow upper portion 60 of the slots being intended to receive only that portion of the screws directly back of their heads. Each casting is secured in an instant, without the use of any tool, by bringing said castings with the broadest portion of 65 their slots e opposite the heads of the screws, introducing the latter therein, and allowing said castings to slide down until the body of each screw becomes lodged into the narrow portion of the slots. The operation is repeat- 70 ed until each casting is in position upon the sides of the frame.

To relieve the screws from side strain in case the shelf on one side is loaded more heavily than on the opposite side, the inner side of 75 the casting E is provided with parallel lugs e', to fit against the side of the vertical pieces B of the frame. To retain the vertical dividing-boards D, the casting is also provided with small lugs e², adjoining its middle portion, 80 and with a flange or a horizontal row of lugs, e³, to support and retain the shelves C. The outer surface of the casting is dressed and japanned or nickel-plated, and presents a tasty appearance. The distance between the shelves 85 can be easily regulated by changing the location of the supporting-screws b. If desired, the shaft A can be retained connected to the yoke or frame by means of a collar, a, secured by a set-screw to said shaft, and having its 90 flange nearly resting upon a pair of the shelves or dividing-boards D.

Although the plates E have been described as castings, they may also be made of sheet metal suitably punched and flanged; and the 95 whole device can be used for the display of dry-goods and other goods, music, &c.

The configuration of the shelf-supporting plates E may also differ from the one shown for different goods.

I am aware that desks and other articles of furniture have been provided with slots in the form of key-hole slots, to receive the head and neck of screws and adapt them to be sus-

pended therefrom; and I do not claim, broadly, the use of slots of this form.

Having now fully described my invention, I claim—

5 1. The combination of the frame having side pieces, B, with shelf-supports having vertical rows of lugs $e' e^2$, arranged parallel with each other, and horizontal rows of lugs or flanges e^3 , substantially as and for the purpose described.

10 2. The combination of the frame having side pieces, B, with shelf-supports having

vertical rows of lugs $e' e^2$, horizontal rows of lugs e^3 , removable shelves resting on the latter, and vertical dividing-boards between the rows of lugs $e' e^2$, substantially as and for the purpose described.

15 In testimony whereof I affix my signature in presence of two witnesses.

JOHN DANNER.
